FINGER NAIL BUFFER

Filed May 27, 1929

FIG. 1

FIG. 2.

FIG. 3.

Inventor:

E. L. Arthur
By Monroe E. Miller

Attorney.

UNITED STATES PATENT OFFICE

ERNEST LEMUEL ARTHUR, OF FAYETTEVILLE, WEST VIRGINIA, ASSIGNOR OF ONE.
THIRD TO CHARLES E. MAHAN, JR., OF FAYETTEVILLE, WEST VIRGINIA

FINGER-NAIL BUFFER

Application filed May 27, 1929. Serial No. 366,339.

The present invention relates to finger nail buffers or polishers, and aims to provide a novel and improved implement of that kind.

Another object of the invention is the provision of a novel flexible buffer element.

A further object is the provision of novel means for detachably connecting the buffer element with a handle, in order that said element may be readily detached and re-10 placed.

With the foregoing and other objects in view, which will be apparent as the description proceeds, the invention resides in the construction and arrangement of parts, as 15 hereinafter described and claimed, it being understood that changes can be made within the scope of what is claimed, without departing from the spirit of the invention.

The invention is illustrated in the accompanying drawing, wherein—

Figure 1 is a perspective view of the improved finger nail buffer or polisher.

Fig. 2 is a longitudinal section thereof.

Fig. 3 is a cross section on the line 3—3 of 25 Fig. 2.

A suitable handle 1 is provided, which may be of metal or other suitable material, and is provided with a longitudinal socket for receiving the clamp 2.

30 The clamp is composed of a doubled strip of resilient metal, the terminals of which are provided with transverse jaws 3 for clamping the butt end portion of the buffer element between them. The diverging arms 35 of the clamp have a tendency to spring apart, and the mouth of the handle socket is preferably tapered, as at 4, so that when the clamp is forced into the socket, the jaws 3 are moved toward one another to clamp the 40 buffer element between them. The outer surfaces of the jaws are preferably grooved or otherwise roughened so as to be conveniently grasped between the thumb and finger of one hand when moving the handle and 45 clamp together or apart.

The buffer element comprises a core or piece 5 of tough second growth wood or other suitable resilient material, and said core decreases in thickness from its butt end to its 50 tip, in order to increase the flexibility of

the buffer element toward the tip thereof. A covering 6 of chamois or other suitable buffing or polishing material is provided on the core or piece 5. Said covering may be secured on the core by double surface adhesive tape 7 disposed between the core and cover, or cement or other adhesive material may be used.

The buffer element composed of the wedge-shaped core and cover thereon may 60 be inexpensively manufactured, so that the buffer element may be replaced economically, especially for use by manicurists so that a new buffer element may be used for each customer.

The free terminal portion of the buffer element is freely pliant, and the cover 6 preferably extends beyond the outer end of the core or piece 5 to be freely flexed toward either side.

By pulling the jaws 3 and handle 1 apart, the clamp may be completely or partly withdrawn from the handle, and the jaws separating will release the buffer element, so that a new buffer element may be readily inserted. By placing the butt end portion of the buffer element between the jaws and pushing the clamp and handle together, the buffer element is clamped between the jaws.

The jaws 3 have flanges 9 at their ends to overlap the edges of the buffer element, and said jaws also preferably have inturned edges or teeth 9 to bite in the cover 6, so that the buffer element is securely held in position coaxial with the handle.

The buffer is convenient and efficient in use, and may be readily carried or stored away.

As shown, the clamp is slipped into the handle, but the handle and clamp may have a screw-threaded connection, if desired.

Having thus described the invention, what is claimed as new is:

1. A finger nail buffer element decreasing in thickness from its butt to its opposite end so that the last named end portion is freely flexible.

2. A finger nail buffer element comprising a flexible core decreasing in thickness from 100

its butt to its opposite end, and a cover of buffing material thereon.

3. A finger nail buffer comprising a buffer element decreasing in thickness from its butt to its opposite end, and a handle attached to the butt end portion of said element.

4. A finger nail buffer comprising a buffer element decreasing in thickness from its butt to its opposite end, a handle, and means for attaching the butt end portion of said element to said handle.

5. A finger nail buffer comprising a handle having a socket, a buffer element, and a spring clamp having diverging arms and jaws on said arms to clamp said element, said arms being movable into said socket and when forced therein being sprung toward one another to clamp said element between said jaws.

6. A finger nail buffer comprising a buffer element, a handle having a socket, and a doubled spring clamp having diverging arms movable into said socket and forced toward one another when moved into said socket, said arms having jaws at their free ends to clamp said buffer element between them.

In testimony whereof I hereunto affix my signature.

ERNEST LEMUEL ARTHUR.
